WILLIAM LAW, OF BIRMINGHAM, ENGLAND.

Letters Patent No. 73,817, dated January 28, 1868.

IMPROVEMENT IN HOOKS AND EYES.

The Schedule referred to in these Letters Patent and making part of the same.

TO ALL TO WHOM THESE PRESENTS SHALL COME:

Be it known that I, WILLIAM LAW, of Birmingham, in the county of Warwick, England, accountant clerk, have invented "a new or improved Dress-Fastening, which said fastening is also applicable to the fastening of belts and bands, and to other like purposes;" and that the following is a full, clear, and exact description of the principle or character which distinguishes it from all other things before known, and of the usual manner of making, modifying, and using the same; that is to say—

This invention relates to an improvement in the manufacture of hooks and eyes, and it consists, first, of a hook whose sides are made of elastic wire, bent into a shape resembling a heart, the two ends of said hook being provided with heads, in combination with an eye of similar shape, having an oval tongue, whereby the elastic sides of the hook are adapted to spring over said tongue, and the heads fit into the contracted space between the tongue and each side of the eye; second, of a hook and eye, the latter constructed of a bar, bent at right angles to the plane, and divided at its ends for engaging with the bent sides of the tongue of the hook, which tongue fits in the angular portion of the eye, the elastic sides of the latter springing open to admit of the attachment, and closing upon the narrow part of the tongue, as will be hereinafter more fully described.

Similar letters of reference indicate corresponding parts.

Description of Drawings.

Figure 1 represents a flat and edge view of my improved eye, and Figure 2 a flat and edge view of my improved hook, the ends of which terminate with large heads, as at *a b*; the sides, in connection with these heads, form springs, to expand when being attached to the eye, and contract to the position as here shown, after the connection or attachment is made, to effect which I apply the heads of the hook in the open space of the eye, indicated by the small dotted circles marked *c d*, fig. 1, and by slightly pulling the hook and eye in contrary directions, the sides *e f* of the hook will expand, allowing the heads *a b* to pass on right and left of the tongue *g*, until the angular parts, with the heads *a b*, are stayed in the contraction of the eye marked *h i*, when the fastening will be complete, and in this form they are represented in flat and edge views at Figure 3. It is not essential that the centre loop or tongue, in the middle of the hook, marked *k k*, in figs. 2 or 3, should be of the shape shown, as it may be so formed as to economize this wire, without interfering in any way with the utility of the fastener; and this I have exhibited in a modification at Figure 4, in which, instead of allowing the ends to terminate with heads, as at fig. 2, I have formed them into a bar, bent at right angles to the plane, and divided in the middle as at *m n*, for engaging with the tongue *l* of the eye, Figure 5, and which eye is slightly modified in its form to that of fig. 1, to the extent of bending the wire outward, to form loops for attachment, instead of inwards, as there exhibited.

This form of hook and eye, made according to my improvements, is exhibited, attached or connected in a flat and edge view at Figure 6, in which it will be seen that the neck of the tongue *l* lies in the angular part of the hook marked *o*, and in forming the attachment the sides of the hook marked *p q*, spring open, to allow the bar to pass over the enlarged part of the tongue, to collapse again by the contracting force of the sides *p q*, to assume its normal condition, which is in close contact, and this mode of attachment I have represented at *R*, Figure 7, in connection with a brace-buckle, the lower part of which, marked *s t*, with the tongue *u*, may be of wire planished down into this form, or otherwise; and the same form of hook, as at *R*, in this figure, I have exhibited at *V*, Figure 8, in connection with a belt-clasp, the tongue in which it engages being marked *v*, and in this case cut out of sheet metal, to form the centre of a clasp, which may be ornamented, or otherwise, on the front as desired, or the tongue part may be made of wire, as at fig. 5, with the loops for attachment altered into the form as at *z*, for the convenience of receiving a belt; and Figure 9 represents a little fastener, with a hook, *y*, made according to my improvements, as exhibited at *R* and *V*, figs. 7 and 8, partly covered over by the part to which it is engaged, by the tongue *z*.

This modification is arranged for fastening garters and such like small bands, but it will be evident that by decreasing its size, and otherwise fashioning the loops, it would be suitable for fastening the backs of dresses, gloves, and other like articles, if preferred; and it will be further seen that if the hook were made as at fig. 2, viz., the ends of the wire terminating with heads *a b*, the same mode would be as applicable in this

case, as also at figs. 7 and 8, as the bar here shown, as described separately at fig. 4, which said figure, as also figs. 1, 2, 5 and 6, are drawn to a somewhat larger scale or size than would be usually required for the purposes hereinbefore stated, in order that its principle or mode of attachment should be clearly defined.

At Figure 10 I have represented a fastening well adapted for a dress-suspender, the part a' , or what may be termed the eye of the fastening, being attached to the upper part of the skirt of a dress by the eyes b' b' , and the hook part, c' , attached in any position at the lower part of the skirt of a dress, or, if desired, one, two, or more rows of these hooks may be used, so that the dress may be looped up to any degree desired, and when so connected or looped together, would present the appearance here shown.

Figure 11 is a detached front and edge view of the eye part a' , and

Figure 12 represents a front and edge view of a modification of this part of the fastening, with the holes or means of attachment represented eyeleted, for the purpose of preventing the cutting of the thread or material used in the attachment of the same to the dress.

Having now given a full description of my invention, and the manner of giving effect to the same, I wish it understood that what I claim as of my invention, is—

The hook and eye, the latter constructed of a bar bent at right angles to the plane, and divided in the middle at $m n$, for engaging with the bent sides of the tongue l , which fits in the angular part, O , of the eye, the sides p and q of the latter springing open to admit of the attachment, and closing upon the narrow part of the tongue l , as herein shown and described:

In witness whereof, I, the said WILLIAM LAW, have hereunto set my hand and seal, this twentieth day of August, in the year of our Lord one thousand eight hundred and sixty-six.

WILLIAM LAW. [L. S.]
